UNITED STATES PATENT OFFICE.

JACOB I. BRORBY, OF SHENANDOAH, IOWA.

SUPPORTING-RACK.

1,192,851.

Specification of Letters Patent.

Patented Aug. 1, 1916.

Application filed July 24, 1915. Serial No. 41,794.

To all whom it may concern:

Be it known that I, JACOB I. BRORBY, a citizen of the United States, residing at Shenandoah, in the county of Page and State of Iowa, have invented certain new and useful Improvements in Supporting-Racks, of which the following is a specification.

This invention relates to supporting or display racks, and in its more intense aspect to racks having devices for temporarily holding articles in suspended position.

While the present invention is susceptible to many applications, as will appear obvious from the description hereinafter set forth, it will be described, however, with relation to its application to a laundry assorting bar in which articles of clothing, or the like, are adapted to be suspended therefrom and automatically counted and assorted.

One of the objects of the present invention is to provide a simple and practical rack of the above character which will be cheap to manufacture and install.

A further object is to provide a self-contained rack having a plurality of independently operated gripping devices which will be durable in construction and easy to manipulate.

A further object is to provide a device of the first above mentioned character which will be reliable, efficient and positive in its action under all conditions.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Figure 1 is a perspective view of the section of a supporting rack showing several

gripping members in operative and released positions; Fig. 2 is a central longitudinal section of the mechanism shown in Fig. 1; Fig. 3 is a perspective view of the modified form of gripping device. Fig. 4 is a smaller perspective view of the rack in use for assorting and counting towels.

Referring now to the drawing in detail and more particularly to Fig. 1, 5 denotes a sheet metal supporting bar of any desired length adapted to be secured to a fixed support by means of bolts or screws passing through holes 6 at the sides thereof. This bar 5 is provided with a longitudinal groove 7 with bent up flanges 8 at each side thereof and between which the gripping devices are mounted. These gripping devices as shown in Figs. 1 and 2, are preferably made of stamped sheet metal and comprise two parts 10 and 11 both substantially L-shaped in longitudinal section. Their adjacent upper ends are provided with laterally projecting lugs or pins 12 adapted to engage holes in the inner sides of the flanges 8 substantially midway between the top and bottom of the groove 7, the member 11 being pivoted slightly farther away from the bottom of the groove than the pivotal support of the member 10.

The member 11 is provided with a punched up T-shaped lug 13 passing through an opening in the member 10 as shown clearly in Fig. 1, in such a manner as to hold the parts in proper position when moved downwardly, as shown in Fig. 1. As the gripping device is released by a movement toward the left in Fig. 1, the gripping jaws 14 at their lower ends release, as shown by the released gripper immediately at the right. This separation is effected by a spring 15 which is connected at one end to a punched up lug 16 in the bottom of the channel 7 and at its opposite end to the lower part of the member 10 at a point 17 slightly below its point of pivotal suspension. Thus, as the member 10 moves about its pivot point, the spring will pass from one side to the other of a dead center position through the pivot point and cause the gripping jaws to snap together either to gripping or released position.

The end of the gripper jaw or member 10 may be turned over, as indicated at 18 to hold a number card 20 for the purpose of identifying the article supported. Thus, for

example, if the device should be used for a coat rack, the coat could be placed in a gripper corresponding with the check handed to the owner of the coat.

5 In Fig. 3, there is shown a modification in which the members 10 and 11 instead of being made of sheet metal, are made of two U-shaped wires 21 and 22 provided with laterally turned ends 23 adapted to engage 10 the same holes in the flanges 8 at each side of the groove 7. These may be covered over with sheet metal members 24 and 25 respectively, to form a more efficient gripping surface and also to hold the parts in proper 15 relative position due to the interlocking engagement at the end 26.

The method of use and operation of a device of this character is substantially as follows: The one side of a room is prefer- 20 ably provided with several vertically disposed racks side by side. The articles to be assorted and counted are suspended from one corner between the gripping jaws 14 of the lowest device as in Fig. 4 and as the 25 gripper is moved to closed position as shown in detail at the extreme left of Fig. 1. The article will thus be firmly clamped there- 30 between and the spring 15 will hold the grippers with a desired degree of tension, as may be necessary. By putting one article of a kind in each device of a rack, one above the other, they will be automatically counted and assorted. On removal of the articles 35 the gripper device is moved upwardly and the spring passing beyond its dead center position, causes the gripper to snap into released position and permit the removal of the article. It is, of course, to be under- 40 stood that the sheet metal members are coated, or otherwise treated to prevent rusting because sometimes the articles are not always thoroughly dry.

It is thus seen that the present invention provides a simple, practical and self-con- 45 tained rack of the above character capable of many uses and applications and designed to accomplish, among others, all of the ob- jects and advantages above set forth.

Without further analysis, the foregoing 50 will so fully reveal the gist of this invention that others can by applying current knowledge readily adapt it for various ap- plications without omitting certain features that, from the standpoint of the prior art, 55 fairly constitute essential characteristics of the generic or specific aspects of this invention, and therefore such adaptations should and are intended to be comprehended within the meaning and range of equivalency of the 60 following claims.

I claim:

1. In a device of the character described, in combination, a channel-shaped rack bar provided with downwardly projecting 65 flanges having holes on their sides and a

gripping device mounted therein comprising a pair of members and a spring associated with one of said members for moving the grippers into operative or into released position.

2. In a device of the character described, 70 in combination, a channel-shaped rack bar provided with flanges having holes on their inner sides, and a gripping device mounted therein comprising a pair of members and 75 a spring associated with one of said members for moving the grippers into operative or released position, said spring being connected with the rack bar and the gripper to move the gripper from one side to the 80 other of a dead center position when moving from released to operative position.

3. In a device of the character described, 85 in combination, a channel-shaped rack bar and a series of grippers mounted therein, each gripper comprising a pair of members pivotally mounted in said rack bar, means connecting said members for holding the same in relatively close position and a spring 90 connected with one of said members for moving the grippers from released to operative position.

4. In a device of the character described, 95 in combination, a rack bar, and a series of grippers mounted therein, each gripper comprising a pair of members pivotally mounted in said rack bar, slidable means connecting said members for holding the same in relatively close position, a spring connected 100 with one of said members, one of said grippers being provided with a flanged lower extremity adapted to hold an identifying card.

5. In a device of the character described, 105 in combination, a single piece of metal bent into channel-form provided with lugs at regular intervals, a series of grippers mounted in said channel bar and a spring connected with one of said lugs and at its opposite end with one of said grippers 110 at a point distant from its support and adapted to swing past a dead center position as the gripper is moved to and from operative position.

6. In a device of the character described, 115 in combination, a single piece of metal bent into channel-form provided with lugs at regular intervals, a series of grippers pivotally mounted in said channel bar, and springs connected with said lugs and one 120 of said members respectively at a point dis- tant from its pivotal support adapted to swing past a dead center position as the gripper is moved to and from operative position, said grippers being made from 125 stamped sheet metal and one of the mem- bers being provided with a punched up lug adapted to engage a slot in the companion member whereby said members are slidably connected with each other.

7. In a device of the character described, in combination, a channel-shaped member and a gripping device pivotally mounted therein and comprising a pair of members
5 slidably connected together and adapted to be brought into operative or gripping relation with each other when swung outwardly from said channel-shaped member and into separated or inoperative relation when swung toward said channel-shaped member. 10
- In testimony whereof I affix my signature in presence of two witnesses.

JACOB I. BRORBY.
